ATTORNEY

WITNESS:

WITNESS:

UNITED STATES PATENT OFFICE.

HARRY D. DELANEY, OF MEMPHIS, TEXAS.

COMBINED SHAVING AND TOOTH BRUSH.

Application filed March 14, 1925. Serial No. 15,579.

To all whom it may concern:

Be it known that I, HARRY D. DELANEY, a citizen of the United States, residing at Memphis, in the county of Hall and State of Texas, have invented new and useful Improvements in Combined Shaving and Tooth Brushes, of which the following is a specification.

This invention contemplates the provision 10 of a combined shaving brush and tooth brush, the parts being so constructed and arranged, that the tooth brush can be folded upon the handle of the shaving brush in a manner to provide a compact article requiring but 15 a minimum of space in a toilet or travelling bag, and when not in use, the heads of the brushes are completely covered, thereby keeping said brushes clean and sanitary.

The nature and advantages of the invention 20 will be better understood when the following detailed description is read in connection with the accompanying drawing, the invention residing in the construction, combination and arrangement of parts as 25 claimed.

In the drawing forming part of this application, like numerals of reference indicate similar parts in the several views, and wherein:

30 Figure 1 is a plan view partly in section. Figure 2 is a longitudinal sectional view showing the position of the tooth brush when not in use.

Figure 3 is a view in elevation showing 35 the position of the tooth brush when in use. Figure 4 is a sectional view taken on line 4-4 of Figure 2.

Referring to the drawing in detail, 10 represents the handle of the shaving brush, 40 which handle is hollow, one end receiving the head 11 of the said shaving brush as shown in Figure 1. This particular end of the handle 10 is threaded to accommodate the threads on a cap 12 which completely covers 45 the bristles of the brush when not in use. The other end of the handle 10 is normally closed by means of a hinged cover 13, which can be conveniently opened to permit access being had to the handle to remove therefrom, 50 either of the containers 14 and 15 respectively, one of the containers containing a shaving cream, while the other contains a tooth paste or powder. These containers are arranged in separate compartments 16 defined by a partition 17 extending throughout 55 the entire length of the handle, and a right

angularly disposed partition 18 which extends throughout a portion of the length of the partition 17. By opening the cover 13 either of these containers can be easily inserted within or removed from its respective compartments. The handle 10 above the partition 17 is provided with a longitudinal groove 19 which groove opens at the outer end of the handle, while the inner end of 60 the groove communicates with an opening 20 formed in the handle to receive the bristles 21 of the tooth brush, the handle of which is indicated at 22. The handle 22 of this brush is pivoted within the groove 19 65 as at 23 at a distance from the outer end of the handle, and when not in use the handle lies within the groove as shown in Figure 2 70 flush with the outer surface of the handle, 75 the bristles 21 projecting through the opening 22 and reposing upon the partition 17. This provides for a very unique and compact arrangement, so that both articles will require but a small amount of space in either 80 a toilet or a travelling bag, and it is manifest upon inspection of Figure 2 that when the 85 brushes are not in use, the bristles are completely protected from dirt and other foreign matter and thus maintained in a clean and sanitary condition. On the other hand either 90 of said brushes can be conveniently used, it being only necessary to remove the cap 12 from the handle 10 for the purpose of using the shaving brush, during which use the tooth brush occupies an out of the way position, 95 inasmuch as it lies flush with the outer surface of the handle 10. When it is desired to use the tooth brush, it is only necessary to swing the brush upon its pivot 23 to the position shown in Figure 3, the tooth brush 100 projecting beyond one end of the handle, and held steady with relation to the handle 10 by being partly received by the adjacent end of the groove 19.

While it is believed that from the foregoing description, the nature and advantages of the invention will be readily apparent, I desire to have it understood that I do not limit myself to what is herein shown and described, and that such changes may be 105 resorted to when desired as fall within the scope of what is claimed.

Having thus described the invention, I claim:

1. In combination, a shaving brush including a handle, having a longitudinal groove and an opening at one end of the 110

groove, a tooth brush including a handle pivoted within said groove and adapted to normally lie flush with the outer surface of the handle, or projected beyond one end of the handle for use, said opening being adapted to receive the bristles of said brush when the latter is in its folded position.

2. In combination, a shaving brush having a hollow handle, partitions dividing the handle into separate compartments, a pivoted cover for the outer end of the handle, said handle having a longitudinal groove and an opening at one end of the groove, and a tooth brush including a handle pivoted within said groove and adapted to normally lie within the latter flush with the outer surface of the handle and projected beyond one end of the handle for use, said opening being adapted to receive the bristles of the tooth brush when the latter is folded.

3. In combination, a hollow handle having a longitudinal groove and an opening communicating with one end of the groove, a tooth brush including a handle pivoted within the groove adjacent the outer end of the

handle, and adapted to lie within the groove flush with the outer surface of said handle when not in use, and projected beyond one end of the handle and partly received by said groove to steady the tooth brush for use, said opening of the handle being adapted to receive the bristles of the tooth brush when the latter is folded upon said handle.

4. In combination, a hollow handle, partitions dividing the handle into separate compartments, a closure for one end of the handle, said handle having a longitudinal groove and an opening communicating with one end of the groove, a tooth brush including a handle pivoted within the groove adjacent one end of the handle, and adapted to normally lie within the groove flush with the outer surface of the handle, the bristles of said tooth brush being adapted to pass through said opening and repose upon the adjacent partition within said handle when the tooth brush is not in use.

In testimony whereof I affix my signature.

HARRY D. DELANEY.
